UNITED STATES PATENT OFFICE.

OTTO HUNTER, OF MILWAUKEE, WISCONSIN, ASSIGNOR, BY MESNE ASSIGNMENTS, TO THE PALMOLIVE COMPANY, A CORPORATION OF DELAWARE.

DESIGN FOR A CAN OR SIMILAR CONTAINER.

Application filed June 26, 1922. Serial No. 2,824. Term of patent 7 years.

To all whom it may concern:

Be it known that I, OTTO HUNTER, a citizen of the United States, residing at Milwaukee, in the county of Milwaukee and State of Wisconsin, have invented a new, original, and ornamental Design for Can or Similar Containers, of which the following is a description, reference being had to the accompanying drawing, forming part thereof.

In the drawing, Fig. 1 is a front view of my new design; Fig. 2 is a side view thereof; and Fig. 3 is a view opposite to that shown in Fig. 2.

I claim:

The ornamental design for a can or similar container, as shown.

OTTO HUNTER.
